Primary Examiner — Philip S Hyder(74) *Attorney, Agent, or Firm* — Mickki D. Murray, Esq.; Parks IP Law LLC(57) **CLAIM**

I claim the ornamental design for an upper vehicle grille, as shown and described.

DESCRIPTION

FIG. 1 is a perspective view of an upper vehicle grille showing the new design;

FIG. 2 is a front view, thereof;

FIG. 3 is a side view, thereof; and,

FIG. 4 is a top view, thereof.

The broken lines illustrate portions of the upper vehicle grille that form no part of the claimed design.
